United States Patent Office

Des. 207,440
Patented Apr. 11, 1967

207,440

SPRAY VALVE

Ernest H. Bucknell, Los Angeles, and Jack K. Rauh and
Irving A. Ward, Hacienda Heights, Calif. (all %
Modern Faucet Mfg. Co., 1700 E. 58th Place, Los
Angeles, Calif. 90001)

Filed June 13, 1966, Ser. No. 2,659

Term of patent 14 years

(Cl. D91—3)

FIG. 1.

FIG. 2.

FIG. 3.

FIG. 4.

FIG. 5. FIG. 6.

FIGURE 1 is a side elevation of our spray valve;
FIGURE 2 is a top plan view of FIGURE 1;
FIGURE 3 is a bottom plan view of FIGURE 1;
FIGURE 4 is an end view from the left as illustrated
in FIGURE 1;

FIGURE 5 is an end view from the right as illustrated
in FIGURE 1;

FIGURE 6 is an enlarged fragmentary end view from
the right as illustrated in FIGURE 1.

It is to be understood that the ribs disclosed fragmentarily in FIGS. 1 through 3 near the rear extend throughout the designated area, as indicated by FIGURE 5.

We claim:

The ornamental design for a spray valve, substantially
as shown and described.
